2 SHEETS—SHEET 2.

UNITED STATES PATENT OFFICE.

LOUIS N. D. WILLIAMS, OF OGONTZ, PENNSYLVANIA.

KNITTING-MACHINE.

1,184,501.

Specification of Letters Patent.

Patented May 23, 1916.

Application filed June 24, 1914. Serial No. 846,945.

To all whom it may concern:

Be it known that I, LOUIS N. D. WILLIAMS, a citizen of the United States, residing in Ogontz, Pennsylvania, have invented 5 certain Improvements in Knitting-Machines, of which the following is a specification.

My invention consists of a machine for producing more rapidly than before, stockings have toes of the type shown in Samuel Henshall's Patent No. 388,678, dated August 28, 1888, that is to say, toes formed by uniting the edges of independently produced tapered webs, one projecting from 15 the instep portion of the foot and the other from the sole portion of the same.

In the accompanying drawings—Figure 1 is a perspective view of the forward end of the foot tube of a stocking with toe-forming blanks produced thereon in accordance with my invention; Fig. 2 is a vertical sectional view of sufficient of my improved knitting machine to illustrate my invention; Fig. 3 is a similar section with the needle-picking devices in a different position from that shown in Fig. 2; Fig. 4 is a similar section with the needle-picking devices in a still different position and with the cam mechanisms differently disposed; Fig. 5 is 30 a diagram illustrating the disposition of the needles in the machine, and Fig. 6 is a view of a special form of needle which may sometimes be employed.

The stocking shown in the Henshall patent before referred to had at the front end of the foot tube two projecting and tapering webs one on the upper or instep half of the foot and the other on the sole or lower half of the foot, and in this respect my improved 40 stocking is similar to that of Henshall, the difference being that whereas, in the Henshall stocking, the toe webs knitted successively, in my stocking the webs 1^b and 1^c are knitted simultaneously and with separate yarns, as indicated respectively by full and dotted lines in Fig. 1. The Henshall stocking was provided around the edge of each of the tapered webs 1^b and 1^c with a band 2 so as to provide a course of stitches 50 for being applied to the points of the looping machine, whereby the toe was closed or completed by uniting the stitches around the edge of the web 1^b to those around the

edge of the web 1^c, and my stocking may or may not be provided with this band, as desired.

In knitting my improved stocking I employ a knitting machine of the circular type and capable of to-and-fro knitting or of both round-and-round and to-and-fro knitting, 60 the needle cylinder of such machine being provided with two semi-circular banks of needles and the machine being also provided with two sets of needle-actuating cam mechanism, one for acting upon the needles of one bank and the other for acting upon the needles of the other bank, each of these sets of cam mechanism having combined therewith needle picking mechanism whereby, during to-and-fro knitting, needle after needle, at the opposite ends of the respective banks can be moved out of operative relation with the knitting cams so as to gradually reduce the number of active needles in each bank and thus gradually reduce the 75 width of the web which is being produced upon the needles.

In knitting to-and-fro a yarn guide is employed in connection with each bank of needles in order to simultaneously produce 80 both of the narrowed webs one with one yarn and one with the other yarn, the needle-actuating cams which operate one bank of needles being set diametrically opposite to those which operate the other bank of needles and one set of needle-actuating cams operating its bank of needles simultaneously with the operation of the other bank of needles by the opposite needle-actuating cams. If it is desired to knit round-and-round, however, one set of needle-actuating cams can be adjusted to a position in line vertically with the other set so that the operation of the needles of one bank follows that of the operation of the needles of the other bank, the needles being actuated in regular succession throughout the entire circle.

Any desired construction of needle picking mechanism may be employed but for the 100 purpose of illustration I have selected that shown in my Letters Patent No. 774,124, dated November 1, 1904, to which reference may be had for a detailed description of the construction and operation of the knitting cams and picking mechanism. In the

accompanying drawings, those members of the needle-operating cam mechanism and of the picking mechanism which it has been necessary to show have been numbered to 5 accord with the numbering of the corresponding parts in the drawings of the patent.

For the purpose of producing the toe portion of the stocking only the lifting pickers are employed as the shaping of the web is effected entirely by a narrowing operation. If, however, the machine is intended to produce a heel pocket upon the foot tube one of the needle-actuating cam mechanisms 10 may be combined with both lifting and depressing pickers as in such case both narrowing and widening operations will have to be performed upon the bank of needles actuated by said cam mechanism in producing the heel.

Referring now to the accompanying drawings, 20 represents the needle cylinder suitably mounted in a fixed holder 21 and carrying two semi-circular banks of needles 23 and 24, the needles 23 having longer stems than the needles 24 so that the projecting butts upon which the knitting cams act are in different horizontal planes and thus provide for the use of two cam rings shown, respectively, at 1 and 1^a, the cam ring 1^a being mounted above the cam ring 1 and carrying cams which act upon the butts of the short needles 24, while the cam ring 1 is provided with cams which act upon the butts of the long needles 23. The rings 1 and 1^a are locked together for joint rotation or reciprocation and the ring 1 is locked to a drive ring 25, the latter being mounted so as to be free to either rotate or reciprocate in a bearing in the main frame or bed 26 and being intended for coöperation with mechanism whereby either rotating or reciprocating movement may be imparted to it in a manner customary in machines of this type.

45 In the present instance the cam rings 1 and 1^a are locked together by means of a spring-actuated bolt 27 and the cam ring 1^a is locked to the drive ring 25 by means of a spring-actuated bolt 28, both of these 50 bolts being carried by the cam ring 1 and being actuated by one and the same spring 29, each bolt having a knob projecting through a slot in the cam ring, whereby the bolts may be retracted to unlocking position or permitted to project into locking 55 position. The cam ring 1^a has two bolt-receiving openings in order to permit locking of the cam rings together either when the needle operating cams are diametrically opposed for to-and-fro knitting, as in Fig. 2, or are disposed almost directly one above the other for round-and-round knitting, as in Fig. 4, and the drive ring 25 may likewise be provided with two bolt-receiving 60 openings in order that the cam ring 1 may

be adjusted to said different positions without corresponding movement of the drive ring, or where such independent adjustment is not necessary the cam ring 1 may be permanently secured to the drive ring and the bolt 28 may be omitted.

In reference to the construction and operation of the needle supporting and actuating members 4, 5, 7, 10, 12, 13, 14, 15 and 18, shown in the drawing, it will be sufficient to say that these parts are constructed and operated in the same manner as the corresponding parts of the machine of my Patent 774,124, before referred to.

In Fig. 2, the parts are shown in position for the picker 10 of the cam ring 1 to act upon the end needles *x* (Fig. 5) of the bank of long needles *y* and the picker 10 of the cam ring 1^a is in position to act upon the end needle *x'* of the bank of short needles *y'*, the cam rings moving in the direction of the arrows shown in Fig. 5. As the pickers 10 are lifted by the cams 15 they are gradually withdrawn from engagement with the butts of the needles, and, by the time the latter have reached their elevated or inoperative position, will be free from engagement with said butts and will be restored to operative position again by action of the springs 14. In knitting round-and-round or in knitting to-and-fro with the full banks of needles, the pickers are moved to and retained in inoperative position by means of the cams 18, as shown in Fig. 4.

Mounted upon the upper end of the needle cylinder 20 is a ring 30 in which are radially guided the web holders 31, radial movement being imparted to these web holders at the proper time by means of a cam ring 32, which is mounted upon the ring 30 so as to be either rotated or reciprocated thereon by engagement of lugs 33 on said ring with a projecting arm 34 which carries a yarn guide 35 and is pivotally mounted upon a bracket 36 projecting upwardly from a ring 37 which is mounted upon and secured to the cam ring 1^a. At the opposite side of the machine is a similar bracket 36 which carries a yarn guide 35^a, the latter being adjusted to position to feed its yarn to the needles during to-and-fro knitting, as shown in Fig. 2, but being raised out of operative relation with the needles, as shown in Fig. 4, or having its yarn severed, when round-and-round knitting is being performed.

The cam which retracts the web holders at the ever-active feed 35 may be fixedly mounted upon the ring 32 but the cam which retracts the web holders at the intermittently-active yarn feed 35^a should, by preference, be adjustable on said ring either to the position shown in Fig. 2 or 3, so as to retract the web holders when said yarn feed 35^a is feeding yarn to the needles, or to the position shown in Fig. 4, so as to

permit said web holders to remain in the projected position when the yarn feed 35^a is moved to non-feeding position.

In producing a toe having oppositely disposed narrowed webs each having an edge band 2, as shown in Fig. 1, the machine will be operated so as to knit to-and-fro until the narrowed webs have been completed, whereupon all of the needles will be adjusted to 10 operative position and the machine will be operated to knit either to-and-for or round-and-round until the desired number of courses for the band 2 have been completed, this band being knitted with both yarns, 15 or with one and the same yarn, as desired.

Where only to-and-fro knitting is necessary, as in producing a stocking web which is two-part throughout, a single cam ring can be used, said ring carrying oppositely 20 disposed sets of cam mechanism each with a needle picker, and both to-and-fro knitting and round-and-round knitting can be effected upon a machine having but a single cam cylinder if the cams are so mounted in 25 the latter as to be susceptible of projection and retraction. In such case the short needles may have long butts, as shown in Fig. 2, and the long needles may have both long butts *w* at the bottom and short butts *w'* 30 between the bottom and top, as shown in Fig. 6.

In knitting to-and-fro upon a machine of this type the oppositely disposed cams will be adjusted so as to act upon the long 35 butts of the respective needles but in knitting round-and-round the upper cams will be projected so as to act both upon the long butts of the short needles and upon the short butts *w'* of the long needles, the lower 40 cams being retracted so as to fail to act upon the long butts *w* of said long needles.

I claim:

1. In a circular knitting machine susceptible of either round-and-round or to-and-45 fro knitting, the combination of two semi-circular banks of needles, and needle-operating cam mechanism and a yarn guide for each bank of needles, each of said needle-actuating cam mechanisms being combined 50 with picker mechanism for moving needles in succession to inoperative position in respect to the cams.

2. In a circular knitting machine susceptible of either round-and-round or to-and-fro knitting, the combination of two semi-circular banks of needles, and needle-operating cam mechanism and a yarn guide for each bank of needles, each of said needle-actuating cam mechanisms being combined with picker mechanism for moving needles 60 in succession to inoperative position in respect to the cams, and one cam carrier being movable in respect to the other, whereby the relation of the cam mechanism to one another may be changed to cause them to 65 act simultaneously upon their respective needles during to-and-for knitting or to follow one another in their action during round-and-round knitting.

3. In a circular knitting machine susceptible of either round-and-round or to-and-fro knitting, the combination of a needle carrier having two semi-circular banks of needles, needle-actuating cam mechanism and a yarn guide for each bank of needles, 75 pickers operating in connection with each cam mechanism, means for adjusting said cam-mechanism in respect to one another, and means for locking them in either of 80 their adjusted positions.

4. In a circular knitting machine susceptible of either round-and-round or to-and-fro knitting, the combination of a needle carrier having two semi-circular banks of needles, knitting cam carriers and yarn 85 guides, one for each bank of needles, pickers operating in connection with each knitting cam mechanism, means for adjusting said carriers in respect to one another, means for locking said carriers in either of their adjusted positions, a driving device for one of 90 said cam carriers, the latter being adjustable in respect to said driving device, and means for locking said cam carrier to said driving device in either of its adjusted positions.

In testimony whereof, I have signed my name to this specification, in the presence of two subscribing witnesses.
